BELT CLEANING DEVICE

William D. Heller, Isabella, Pa., assignor to
 National Steel Corporation, a corporation of
 Delaware

Application May 10, 1946, Serial No. 668,875

4 Claims. (Cl. 198—230)

1

This invention relates to an improved device for removing foreign material from belts.

Where belts are exposed to outside weather conditions, there is a tendency for ice and snow, and slime to accumulate on the belts. Conveyor belts are often used for transporting coal, coke, ore and other materials and particles of these materials tend to adhere to the belt after passing the discharge end of the conveyor. Such accumulations of foreign materials interfere with the proper operation and function of the belt and the problem of preventing accumulations is especially acute for belts exposed to outside weather conditions although the problem is not confined to such locations.

Various types of belt cleaning devices have been suggested. Power-driven, rotary brushes have been proposed but they are readily clogged by ice and snow and are relatively expensive to install and maintain. Both stationary and resiliently supported scraper blades mounted on leaf springs or counter-balanced arms have been proposed. The stationary blades cause excessive wearing away of the elements, while the resiliently supported blades tend to chatter which results in non-uniform removal of the accumulated foreign material. Consequently, the cleaning devices of the prior art have not been entirely satisfactory.

A primary object of this invention is to provide an improved belt cleaning device for removing ice, moisture, slime, and other foreign materials that does not become clogged even when used under extremely adverse conditions.

A further object of this invention is to provide a belt cleaning device which will not chatter and which will uniformly remove all of the foreign material adhering to the belt.

It is also an object of this invention to provide an improved belt cleaning device which is economical to install and maintain, which is efficient in operation, and which is sufficiently sturdy to have a relatively long operating life.

The present invention provides an improved belt cleaning device which includes at least one and preferably a plurality of metal scraper blades. The blades are supported in a novel manner so that they do not chatter, do not become ineffective from fouling of the blades with accumulated foreign material and do not damage the belt or cause excessive wearing away of the elements. This is achieved by providing resilient means separately urging the opposite end portions of the cleaning blades toward and into contact with the surface of the belt being

2

cleaned whereby the blade end portions have substantially independent floating movement toward and away from the belt surface.

These and other objects and advantages will become more apparent when considering the following description along with the accompanying drawings, in which:

Figure 1 is an isometric view of a belt cleaning apparatus embodying the principles of the present invention;

Figure 2 is a side elevational view of the apparatus of Figure 1 in position for cleaning a belt; and

Figure 3 is an enlarged fragmentary view taken along the line 3—3 of Figure 1 and showing the details of the support at one end of one of the belt cleaning blades.

The belt cleaning device 10 is mounted on a suitable support 11 adjacent a belt 12 having a surface 13 on which foreign material tends to accumulate. The belt 12 may be supported in any suitable manner and is here shown as passing about a pulley 14 which rotates in a clockwise direction. The means for driving the belt 12 is not shown. The support 11 for the cleaning device 10 may be a separate support or may be part of the belt supporting apparatus.

The belt cleaning device 10 includes a first pair of corner posts 16 and 17 and a second pair of corner posts 18 and 19. Each corner post is similarly supported at its lower end on support 11 and with its upper end extending through a bracket 20 rigidly supported in any suitable manner. Each corner post is preferably slidable through member 20 so as to facilitate dismantling of the cleaning device. There is an adjustable, normally fixed collar 22 with a set screw 23 on each corner post. A second collar 24 is slidably mounted on each post. A spring 25 encircles each post between each pair of collars 24 and 22, and urges the corresponding collar 24 upwardly toward surface 13 of belt 12.

Belt blades 26 are removably mounted in a supporting frame 27 so that they extend in a direction diagonally across the surface 13. The support 27 includes a pair of cross-members 29 and 30 extending transversely of the belt surface 13. The cross-member 29 supports the end portions 31 of blades 26 and is connected at each of its ends through a rod 33 to the slidable collar 24 mounted on the corresponding one of the first pair of corner posts 16 and 17. The other cross-member 30 supports the opposite end portions 32 of blades 26 and is similarly connected through corresponding rods 33 to the slidable

collars 24 on the pair of corner posts 18 and 19. The end of each cross-member and the corresponding rod 33 and collar 24 are so constructed and arranged that each cross-member may tilt relative to the collar 24 and so that frame 27 may tilt and properly position itself and blades 26 in response to variations in the slop of belt 12. End member 34 extend between and are connected to the end portions of the cross-members 29 and 30. The end members 34 may be omitted.

With this construction, the springs 25 on posts 16 and 17 resiliently urge cross-member 29 and the end portions 31 of blades 26 toward and into contact with the surface 13 of belt 12 and the other springs 25 on posts 18 and 19 resiliently urge the cross-member 30 and the end portions 32 of blades 26 toward the surface 13. Thus, the opposite end portions 31 and 32 of the blades 26 are separately, resiliently urged toward the surface 13 and the blade end portions have independent floating movement in direction toward and away from the surface 13 which decreases harmful abrasion; eliminates chatter and results in more uniform cleaning; all as will be more fully pointed out when describing the operation of the cleaning device.

The blades 26 may be formed of any suitable material but are preferably formed of metal. Metal blades are more nearly self cleaning and do not as readily accumulate ice during winter or become clogged as do fabric or rubber composition blades. Further, the blades are readily removable from the cleaning device which facilitates replacement and repair. As shown in Figure 1, the member 29 contains a slot 36 for removably receiving the end portion 31 of each blade 26. The slot 36 has a bottom surface (Figure 3) on which the blade end is supported and an end surface 38 which prevents lengthwise shifting of the blade. The other end portion 32 of each blade 26 is similarly supported in member 30.

Prior to or during operation of the belt cleaning device 10, the set screws 23 may be loosened and the collars 22 individually vertically adjusted so that each spring 25 pushes upwardly the proper amount and the collars then locked in position by tightening the screws 23. Normally, the blades 26 will be urged against the belt surface 13 but in some locations it may be desirable to have the upper edges of the blades normally spaced from the belt surface 13 a slight amount. By spacing the blade edges from the belt, friction and abrasion are reduced to a minimum while accumulations of appreciable quantity are removed.

When the pulley rotates in a clockwise direction and the return side of belt 12 moves towards the left as indicated in Figure 2, the belt does not move in a straight line or in a fixed plane, but will undulate. With the present device the blade supporting frame 27 and the blades can readily tilt to follow both the longitudinal and transverse undulations of the belt so as to maintain a maximum amount of each blade in contact with the belt. An abrupt wave in the belt or a protuberance on the belt surface will often be moving at sufficient speed so that the impact against the blade will tend to drive the blade away from the belt with sufficient momentum so that there is a tendency for the blade to move completely away from the belt surface. With the present device, if a protuberance strikes an end portion of

blade, the opposite end portion is not moved away from the belt as the opposite end portions of the blades have separate floating movement. Thus, the present invention also eliminates or greatly reduces all tendency of the blades to chatter. When blades chatter, they do not uniformly remove the accumulations and clean the belt.

I claim:

1. A device for cleaning a surface of a moving belt comprising a belt cleaning blade; a first cross-member extending transversely of the belt surface and supporting one end portion of the blade; a second cross-member extending transversely of the belt surface and supporting the opposite end portion of the blade; a slot in each of said cross-members for removably receiving the corresponding blade end portion; and means for urging each cross member toward the belt surface.
2. A device for cleaning a surface of a moving belt comprising a belt cleaning blade having a bottom and opposite end surfaces; a first cross-member extending transversely of the belt surface and supporting one end portion of the blade; a second cross-member extending transversely of the belt surface and supporting the other end portion of the blade; a slot in each cross-member for removably receiving the corresponding blade end portion; each slot including a bottom surface adapted to engage the bottom blade surface to support the blade and an end surface adapted to engage the corresponding blade end surface; and resilient means separately urging each cross-member toward the belt surface whereby the blade end portions have independent floating movement in a direction toward and away from the belt surface.
3. A device for cleaning the surface of a moving belt, said device comprising a first cross member extending across the belt surface, a second cross member spaced from and extending across the belt surface, a plurality of cleaning blades supported on the cross members in spaced apart, parallel relationship, each blade having one end supported on the first cross member and having the other end supported on the second cross member and extending diagonally of the direction of belt movement so that each blade extends diagonally partially across the belt surface, each cross-member being slideably mounted at opposite ends on a pair of posts for movement toward and away from the belt surface, an independent resilient means at each post urging the respective end of a cross member toward the belt surface whereby the opposite ends of the blades are independently urged toward the belt surface and whereby the opposite ends of each cross member are independently urged toward the belt surface.
4. A device for cleaning the surface of a moving belt, said device comprising a first cross member extending across the belt surface, a second cross member spaced from and extending across the belt surface, a plurality of cleaning blades supported on the cross members in spaced apart parallel relationship, each blade having one end supported by the first cross member and having the other end supported by the second cross member and extending diagonally of the direction of belt movement so that each blade extends diagonally partially across the belt surface, a slot in each cross member for each blade and each slot removably receiving the corresponding blade end portion of a respective blade, each cross

member being slideably mounted at opposite ends on a pair of posts for movement toward and away from the belt surface, and independent resilient means at each post urging the respective end of a cross member toward the belt surface whereby the opposite ends of the blades are independently urged toward the belt surface and the opposite ends of each cross member are independently urged toward the belt surface.
